OTHER PUBLICATIONS

U.S. Design patent application Ser. No. 29/175,612, filed Feb. 7, 2003, Tape Dispenser.

Primary Examiner—Martie K. Holtje

(74) Attorney, Agent, or Firm—George W. Jonas

(57) **CLAIM**

The ornamental design for a desktop tape dispenser, as shown and described.

DESCRIPTION

FIG. 1 is a perspective view showing the new design for a desktop tape dispenser.

FIG. 2 is a left side view showing the new design for a desktop tape dispenser.

FIG. 3 is a right side view showing the new design for a desktop tape dispenser.

FIG. 4 is a top view showing the new design for a desktop tape dispenser.

FIG. 5 is a bottom view showing the new design for a desktop tape dispenser.

FIG. 6 is a front view showing the new design for a desktop tape dispenser; and,

FIG. 7 is a back view showing the new design for a desktop tape dispenser.

The structure depicted by means of broken lines in the figures has been shown for illustrative purposes only and forms no part of the claimed invention.
